UNITED STATES PATENT OFFICE.

ARTHUR U. MERSHON, OF EXCELSIOR SPRINGS, MISSOURI, ASSIGNOR OF ONE-FIFTH TO OTIS HOLMES, ONE-FIFTH TO A. M. HOWARD, ONE-FIFTH TO A. G. ARNOLD, ONE-FIFTH TO A. D. BLOCH, AND ONE-FIFTH TO O. L. MERSHON, ALL OF EXCELSIOR SPRINGS, MISSOURI.

VENDING-MACHINE.

1,257,909.

Specification of Letters Patent. Patented Feb. 26, 1918.

Application filed August 8, 1916, Serial No. 113,794. Renewed July 20, 1917. Serial No. 181,861.

To all whom it may concern:

Be it known that I, ARTHUR U. MERSHON, a citizen of the United States, residing at Excelsior Springs, in the county of Clay and 5 State of Missouri, have invented new and useful Improvements in Vending-Machines, of which the following is a specification.

The present invention relates to improvements in coin or check controlled package 10 vending machines, and the primary object of the invention is to improve and simplify the existing art by producing a machine of this character comprising few simple parts which are positive in their action so that 15 only a single package can be delivered at one operation of the device and so that the device cannot be operated by other than the proper coin or check.

With the above and other objects in view 20 the improvement resides in the construction, combination and arrangement of parts set forth in the following specification and falling within the scope of the appended claims.

25 In the drawings:

Figure 1 is a perspective view of a machine constructed in accordance with the present invention,

Fig. 2 is a vertical transverse sectional 30 view through the device taken in a line with one of the arms of the delivery member,

Fig. 3 is a similar sectional view taken centrally through the coin or check chute,

Fig. 4 is a sectional view approximately 35 on the line 4-4 of Fig. 3,

Fig. 5 is a sectional view illustrating the manner in which the coin is released from the delivery and actuating means,

Fig. 6 is a perspective view of the de- 40 livery means, and

Fig. 7 is a similar view of the actuating means.

The casing 1 of the device may be of any desired material, size and shape, that illus- 45 trated by the drawings being of a substantially rectangular box-like formation having one of the sides thereof provided with a door 2 which forms access to the actuating mechanism as well as to the coin tray and 50 is also provided with a hinged top 3 whereby articles to be vended may be inserted in the hopper. The top is of course normally locked upon the receptacle and the said top is provided with a slot 4 that communicates

with the coin or check chute 5. The chute 5 is arranged directly to the rear of the hopper 6, the said hopper being arranged at or adjacent to the front face of the casing and the said front face of the casing terminates a suitable distance above the 60 bottom of the casing, and the lower wall of the opening thus provided has arranged thereon a curved plate 7 providing what may be called a tray, the said tray being arranged directly below the hopper 6 receives the 65 articles from the said hopper when the same are delivered in a manner which will presently be described.

The chute 5 is arranged approximately centrally of the hopper and the rear wall of 70 the hopper forms the front wall of the chute, the said wall preferably being constructed of metal, and the said wall to the opposite sides of the chute is slotted both vertically and transversely to provide spring holder 75 members 8. The dividing wall between the hopper and the chute, indicated for distinction by the numeral 9, centrally and at the lower end thereof is provided with a rounded cut-away portion 10 and the rear wall of the 80 chute 5 is likewise provided with a similar cut-away portion 11 alining with the said cut-away portion 10, and the width of these slots corresponds with the diameter of the 85 coin or check employed in operating the device.

The delivery means comprises a plate 12 which is hingedly secured, as at 13, to the rear wall 9 of the hopper 6, the hinged members 13 being spring actuated whereby to 90 force the plate 12 against the rear wall 14 of the chute. The plate 12, at the upper edge thereof, is provided with cam members 15-15, each of said cams being disposed in a line with each of the spring holders 8 and adapted, when the plate 12 is swung rearwardly of the casing (in a manner and for a purpose which will presently be set forth) to contact with the said holders and force the same to within the hopper 100 6 whereby to grip the article in the hopper nearest the delivery end thereof and thus prevent the delivery of more than one article or package at a single operation of the device. The plate 12, at the lower edge 105 thereof is provided with an angular outwardly extending flange 16, the same forming a shelf to receive the lowermost pack-

age in the chute, or the package directly below the holder members 8. The flange 16 is centrally cut-away in a line with the openings 10 and 11, the side walls provided by 5 the opening at the inner terminal of the said opening being projected toward each other or otherwise provided with extensions 17-17, the said extensions being spaced a sufficient distance to grip or engage with 10 the opposite edges of the check or coin 18 slightly above the central cross sectional diameter thereof. The flange 16, to the opposite sides of the referred to opening are provided with curved arms 19-19, and one of 15 these arms, at the outer edge thereof, is formed with an angular cam-shaped extension 20, and this extension is adapted to frictionally contact with the upper edge of the curved tray 7, whereby to retain the delivery means in open or delivery position to 20 assure the package being received upon the tray. It is, of course, to be understood that the arms 19 as well as the shelf of the delivery means are suitably covered by the 25 outer plate of the casing, so that the device can not be fraudulently actuated.

The rear plate 12 of the delivery means, central of the coin or check receiving opening in the shelf thereof is provided with a 30 pair of depending spaced fingers 21-21, while the numeral 22 designates a hood or shield member disposed to the rear of the hopper and the chute and having its upper curved edge connected with both the hopper 35 and chute. This hood 22 at the upper and curved portion thereof is provided with an elongated slot 23, and secured to the upper portion of the hood or to the rear of the coin chute is a spring member 24 that 40 is provided with a rounded or curved portion 25 that is projected through the slot 23 and the rounded portion of the said spring 23 is adapted to be received between the fingers 21 when the delivery means is 45 swung to delivery position to eject the coin from between the flanges or extensions 17-17 provided in the slot of the shelf 16 and to allow the coin to drop in the portion of the 50 device between the tray 7 and the hood 22 into what may be termed the coin-receiving portion of the device.

The actuating means comprises a substantially U-shaped bar, the lower member 26 of which having its inner edge centrally 55 notched in a line with the openings 10 and 11 as well as with the opening in the flange or shelf 16 of the delivery means. The angular side arms 26' of the actuating member or means are pivotally secured, as at 60 27, to the rear of the hopper and to the rear of the chute, and the pivot 27 may provide an extension of the pivot member which hingedly connects the delivery means or member to the device. One of the side members 26 is provided with an angular exten-

sion 28 which has its end outturned, as at 29, to provide the operating handle for the actuating means, the said handle projecting through a curved slot 30 in one of the sides of the casing.

The slot in the member 26 of the actuating device is so arranged that the inner wall provided thereby will contact with the lower edge of the check or coin 18, and the gripping engagement of the coin or check with 75 the members 17-17 will cause the delivery means to be swung inwardly of the casing when the handle 29 of the actuating means is operated to move the said actuating means in such direction, and the contacting engagement of the coin by the spring releasing member 24 will eject the coin, as previously described. The actuating member or means is under the influence of a spring 31 whereby the same is normally moved to coin-receiving position and the member 26 of the said actuating means will, when pressure upon the handle 29 is relieved, engage with the cam 20 upon one of the arms 21 to move the same out of frictional contact with the 80 upper edge of the tray 7, thus permitting the springs of the delivery means to return the same to initial position. It should be stated that the arms 19 are constructed of some suitable spring material whereby to 85 insure the co-engaging of the cam 20 with the upper edge of the tray 7.

The coin chute is, of course, of a size to receive only the proper coin or check for actuating the device. Therefore a check of a 90 greater diameter than the required diameter will not be admitted to within the chute, while should a check of a smaller diameter than that required in the proper operation of the device be passed through the chute 95 the same would also pass through the notched portion of the actuating member and be delivered to within the coin tray or receptacle, and from the above it is believed that a further description of the construction and 100 operation of the device is not necessary.

Having thus described the invention, what I claim is:

1. In a check controlled package vending machine having a hopper through which the packages gravitate and a check chute arranged at the rear of the hopper, of spring holder members in the rear wall of the hopper, a delivery member hingedly secured in the casing to the rear of the chute and 115 hopper, cam members upon the delivery member disposed to contact with the holder members to force the same inward of the hopper when the delivery member is swung to delivery position, said delivery member including a shelf disposed below the chute and below the hopper and said shelf having a notched portion registering with the inner 120 side walls of the chute, a pivoted actuating member, spring means for normally swing- 125 130

ing the actuating member to one position to retain an element thereof below the shelf of the delivery member, said element of the actuating member having a notch disposed 5 to align with the notch in the delivery member and whereby to engage with a check when the same is passed through the chute to engage with the notch of the delivery member to lock the delivery end of the actuating members, and means for ejecting the 10 coin when the actuating member and the delivery member are swung to uncover the mouth of the chute and the mouth of the hopper.

15 2. In a check controlled package vending machine, the combination with a casing having a hopper and a check chute therein, and a curved tray disposed below the hopper and chute, of spring holder members in the 20 rear wall of the hopper, a delivery member including a plate which is hingedly secured to the rear wall of the hopper, cam members upon said plate disposed to engage with the holder members to force the same to 25 within the chute when the delivery member is swung to delivery position, means, comprising springs for normally sustaining the delivery member in one position, said delivery member including a shelf which is 30 disposed below the chute and hopper, curved spring arms upon the shelf one having its outer surface provided with a cam, and which is adapted to contact with the upper edge of the tray when the said member is 35 swung to delivery position, said tray having a notch disposed in a line with the opening of the chute to receive and engage with a check, an actuating means including a hinged member having an element disposed 40 below the notched portion of the shelf and said element having its inner surface notched whereby to engage with the edge of the check and to lock the actuating means with the delivery member, a handle for the actuating member, and a spring member within 45 the casing disposed to contact with the coin to eject the same from between the delivery and actuating members, when the said members are swung to uncover the hopper and chute, and said actuating member adapted 50 to contact and release the cam from engagement with the tray when the actuating member is returned to its normal position.

3. In a check controlled package vending machine, the combination with a package 55 hopper and a check chute, and said hopper and chute having their lower edges provided with alining rounded openings, of spring package holder members upon the rear wall of the hopper, a delivery member 60 including a plate having spring hinges connecting the same with the rear wall of the hopper, said plate having cam members arranged to contact with the holder members to force the same to within the hopper when 65 the delivery member is swung to delivery position, the delivery member also including a shelf which is disposed below the hopper and chute, said shelf having a central opening, and the rear plate of the delivery member having a pair of spaced depending fingers arranged centrally of the opening, a 70 holder member comprising side arms and a connecting member for the arms, a pivot connecting the arms to the rear of the chute, 75 one of said arms being extended angularly and having its end outturned to provide a handle, the connecting member for the arms being centrally notched upon its inner edge and whereby the actuating member is locked 80 to the delivery member, and a curved spring member disposed to the rear of the delivery and actuating member and adapted to be received between the delivery and actuating members, when the said members are swung 85 in the direction of the spring.

In testimony whereof I affix my signature.

ARTHUR U. MERSHON.
